UNITED STATES PATENT OFFICE.

NILS W. NORDSTROM, OF BROOKLYN, NEW YORK.

ARTIFICIAL DENTURE.

1,252,291.

Specification of Letters Patent.

Patented Jan. 1, 1918.

Application filed October 2, 1916. Serial No. 123,312.

To all whom it may concern:

Be it known that I, NILS W. NORDSTROM, a citizen of Sweden, and resident of the borough of Brooklyn, in the county of Kings and State of New York, have invented certain new and useful Improvements in Artificial Dentures, of which the following is a specification.

This invention relates to means for connecting together different parts of an artificial denture, and it appertains more especially to an improved construction of stud and socket members adapted for interengagement between the contiguous surfaces of a crown placed upon a natural tooth and the proximate end of a dental bridge designed to fill a vacuity in the alveolar process.

One of the objects of the invention is to provide a pair of co-acting members of the character described with similar means for attaching each of them separately to the parts that are to be supported one from the other in the bridge work.

Another object is the provision of extended attaching means on both the stud and socket members which will admit of being spread and fitted over comparatively large areas of their respective parts of the denture, thus facilitating accurate adjustment and affording ample support therebetween.

A further object is to produce associated members of the species mentioned having interfitting elements which shall be properly guided laterally as well as longitudinally, and held against endwise movement in one direction.

Still another object is the production of members of the type specified which shall be simple, strong, durable, easy to apply, and at the same time amenable to low cost of manufacture.

Other objects and advantages will become apparent as the specification proceeds.

With the aforesaid objects in view, the invention consists of the improvements, novel construction, arrangements and combinations of parts hereinafter described, defined in the subjoined claims, and illustrated in their preferred embodiments by the annexed drawings, wherein like elements are designated by the same reference characters throughout.

In the said drawings, the several views are all made on an enlarged scale to better illustrate the distinguishing features of the invention.

Figure 1 is a face view of the stud constituting one of the dual members above mentioned;

Fig. 2 is a rear view of the socket included in the pair of members;

Fig. 3 is an end view of both members, interconnected;

Fig. 4 is a vertical transverse section through the center of the interconnected members, the section being on the line 4—4 of Fig. 3, looking in the direction of the arrows; and

Fig. 5 is a top plan view, partly in section, showing one embodiment of the invention, in which the conjoined stud and socket members constitute the connecting medium between a tooth cap and a bridge in a denture.

Fig. 6 is a side elevation of the same embodiment of the invention; and

Fig. 7 is a central longitudinal section of the structure shown in Fig. 5.

In these views the reference numerals 11 and 19 denote, respectively, the receiving and the engaging elements in the stud and socket members, by means of which the separate parts of the said denture are joined one with the other.

Preferably, the receiving element 11 is made circular in cross section and of elongate barrel formation, having one end 12 open for the insertion therein of the co-acting element 19. The other end 13 of the barrel shaped element may remain closed to serve as a stop for the corresponding end of the said co-acting element to abut against. The closed end of the barrel and the abutting terminal of the element can be made straight as shown in Figs. 1, 2 and 4, or in any other preferred form. One side of the barrel has a longitudinal opening, as at 14, the edges of which are turned outwardly in opposite directions so as to form a pair of lateral flanges 15. These two flanges are interconnected at one end of the barrel by a similar flange 16, presenting therewith a broad, flat, bearing plate composed of three parts, all projected from the barrel in a single plane approximately. The material composing this triple or three part bearing plate is preferably annealed or made softer than that from which the barrel is formed, in order that it may readily adapt itself to the face of the article, such as the bridge, crown, or other object to which it is to be applied.

The aforementioned engaging element 19 is designed to fit the inside of the barrel or receiving element above described. To this end, the said engaging element is of similar body configuration as the said receiving element, and further is provided with a fin or lateral extension 20, adapted to slide through and along the previously mentioned opening 14 of the barrel. At the outer edge 10 of this fin is also formed a tripartite, substantially level bearing plate similar to that of the receiving element, and likewise composed of two oppositely extending lateral flanges 21, and a connecting end flange 22. 15 Fig. 3 shows the latter named flanges of the bearing plate as being curved differently from the bearing plate provided on the receiving element, but in practice both bearing plates may be of exactly the same shape. 20 In Fig. 5 is shown by way of example, one of several uses to which a pair of the stud and socket members herein disclosed may be applied. As represented in this view, the bearing plate formed by the combined 25 flanges 21, 22 of the stud member is fitted to the front side of a cap 25, covering a molar tooth, while the opposed tripartite bearing plate, composed of the flanges 15, 16 of the socket member, is attached to the adjoining rear end of a dental bridge 26. The receiving element 11 and the engaging element 19, it will be seen, constitute interlocking parts between the two bearing plates. This makes a firm joint possessing various 30 beneficial features, and particularly the advantage of permitting the forward end of the bridge to be rigidly secured to another cap 27, also covering a tooth, for instance, a bicuspid. Manifestly, it is conducive to better workmanship and all around convenience to have the bridge solidly attached to a cap or equivalent anchor at one end, and then to align the guiding surfaces of the stud and socket members while adjusting 35 the latter in parallelism with one side of a single tooth, than to be obliged to dress the opposed faces of two teeth so that they will lie in parallel planes respectively adapted to accommodate the bridge at both extremities. 40 It is understood that the flanges 21, 22 of the stud member 19 and the flanges 15, 16 of the socket member 11 are originally made larger than is necessary and that the surplus portions of the said flanges, such as appear 45 at 28, 29 in Figs. 5 and 6, and any similar excess of metal or other material employed, are carefully trimmed off and eliminated while the denture is being prepared. When finally setting the caps 25, 27 and the bridge 50 26, together with the intermediate stud and socket members in their assigned positions, a suitable cement is applied to the interfitting surfaces of the caps and anchoring teeth therein, as well as to the contacting 55 sides of the receiving and engaging elements 60 65

11, 19 and the flanges thereof where they face one another.

The chief advantage of the before described construction and method of procedure is that a large double bearing surface 70 is provided for the jointed ends of the denture when the flanges of the stud and socket members are placed in juxtaposition which is conducive to better holding power between the parts that are united. Furthermore 75 15 it is only necessary to take care of one alignment for the bridge, whereas with previous methods and structures it was required to align the bridge from both ends, once for each anchoring tooth, and often 80 times the sides of the anchor teeth had to be dressed, which was injurious to them besides being painful to the patient.

Although the stud and socket members aforesaid have been described and illustrated in conjunction with a molar tooth cap and a dental bridge thereto attached, no limitation in that sense is intended, as these studs and sockets can be applied and utilized wherever an accurate and secure connection 90 is required between two or more parts of an artificial denture, or similar structure.

While a certain preferred embodiment of this device has been shown and described, it will be understood that changes in the form, 95 arrangements, sizes, proportions and details thereof may be made without departing from the scope of the invention as defined by the appended claims.

Having described my invention what I 100 desire to secure by Letters Patent and claim is:—

1. A dental joint including opposed artificial supports designed to be brought together in juxtaposition, a pair of intermediate plates separately attachable in substantial parallelism one to each of said supports, and coating interengaging elements respectively carried by said plates, one of said elements consisting of a stud extending 110 partly up the face of its plate, and the other element being a socket of corresponding height formed in the face of the opposite plate.

2. A dental joint including approximately 115 parallel plates arranged to adhere closely frontwise one to the other, and centrally contracted retainers projecting respectively therefrom in position for interengagement on the same side of both plates, one of said 120 retainers being composed of a stud of limited height and a web therefor joining the same to its plate, and the other retainer consisting of a socket commensurate with said stud originating in the other plate at the point 125 of intersection with said web.

3. An artificial denture including a retainer adapted to be fixed to a tooth, a second retainer attachable to another tooth at a certain distance in line therewith, a bridge 130

rigidly held to the latter named retainer at one end, a pair of plates located in a space intervening between the other end of said bridge and the first mentioned retainer, co-
5 acting interengaging elements carried by said plates, and filling on opposite sides of the plates serving to fasten one of them to the first retainer and the other one to adjoining end of the bridge in such a manner
10 that a single joint between the said elements is obtained parallel to the plane of perma-

nent attachment of the distant retainer with its tooth.

Signed at the borough of Manhattan, in the county of New York and State of New 15 York, this 29th day of September, A. D. 1916.

NILS W. NORDSTROM.
